UNITED STATES PATENT OFFICE

117,225

DESIGN FOR A DRESS

Josephine Chambart, New York, N. Y.

Application September 12, 1939, Serial No. 87,147

Term of patent 3½ years

To all whom it may concern:

Be it known that I, Josephine Chambart, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

I claim:

The ornamental design for a dress, substantially as shown.

JOSEPHINE CHAMBART.
